(57) CLAIM

The ornamental design for a battery, as shown and described.

DESCRIPTION

FIG. 1 is a top perspective view of a battery, showing our new design.

FIG. 2 is a bottom perspective view thereof.

FIG. 3 is a rear elevational view thereof.

FIG. 4 is a front elevational view thereof.

FIG. 5 is right-side elevational view thereof.

FIG. 6 is a left-side elevational view thereof.

FIG. 7 is a top plan view thereof.

FIG. 8 is a bottom plan view thereof; and,

FIG. 9 is a bottom perspective view of a battery, showing a second connector type in broken lines.

The broken lines showing connectors and controls are for the purpose of illustrating unclaimed subject matter and form no part of the claimed design.
